UNITED STATES PATENT OFFICE.

HIRAM R. SUITS, OF ESCANABA, MICHIGAN.

CURRYCOMB.

1,121,687.

Specification of Letters Patent. Patented Dec. 22, 1914.

Application filed March 9, 1914. Serial No. 823,619.

To all whom it may concern:

Be it known that I, HIRAM R. SUITS, citizen of the United States, residing at Escanaba, in the county of Delta and State of Michigan, have invented certain new and useful Improvements in Currycombs, of which the following is a specification, reference being had to the accompanying drawings.

10 This invention relates to an improved curry comb and has for its primary object to provide improved means for easily, quickly and thoroughly cleaning the teeth of the comb.

15 A further and more specific object of the invention resides in the provision of a cleaning plate hingedly mounted at one of its ends upon the body plate and provided with individual slots for the reception of the several rows of comb teeth, and means on the opposite end of the cleaning plate for retaining the same in its closed position with respect to the comb body.

20 The invention has for still another object to generally improve and simplify the construction of devices of the above character and to produce a cleaning device for curry combs which is extremely simple in its construction, serviceable and convenient in practical use and capable of manufacture at comparatively small cost.

25 With the above and other objects in view as will become apparent as the description proceeds, the invention consists in certain constructions, combinations and arrangements of the parts that I shall hereinafter fully describe and claim.

30 For a full understanding of the invention, reference is to be had to the following description and accompanying drawing, in which—

35 Figure 1 is a top plan view of a curry comb embodying my invention in its preferred form; Fig. 2 is a bottom plan view 40 of the comb, the cleaning plate being in its open position; Fig. 3 is a section taken on the line 3—3 of Fig. 1.

45 Referring in detail to the drawing, 5 designates the body of the curry comb which is provided upon its edges with the toothed flanges 6. Plates 7 of channel form in cross section are secured upon this body plate between the flanges 6 thereof and are also provided with tooth rows indicated at 8. 50 These channel plates may be riveted or otherwise secured upon the body plate. To

the securing studs or rivets 9 for the plates 7, which project above the upper face of the comb body, a substantially U shaped rod 10 is secured, the intermediate portion of 60 said rod being extended to form a suitable handle 11.

12 indicates the cleaning plate which is of rectangular form and of slightly greater dimensions than the body plate 5 of the 65 comb. The edges of this cleaning plate are turned over a reinforcing or strengthening wire indicated at 13, and to one end of said plate hinge links 14 are attached, the other end of said plate being engaged upon one 70 end of the U shaped rod 10. The opposite end of the cleaning plate is provided with a spring latch member indicated at 15 which is designed for engagement over the corresponding end of the body plate 5 to retain 75 the cleaning plate in its closed position upon the comb body.

The cleaning plate 12 is provided with a plurality of parallel longitudinal slots 16 and these slots are adapted to receive the 80 respective rows of comb teeth 6 and 8.

From the above description taken in connection with the accompanying drawing, it will be understood that when the plate 12 is in its closed position, the rows of cleaning teeth project through the slots 16 thereof and the device is adapted to be used in the ordinary manner in currying horses and other animals. The hair or other refuse matter collects upon and between the rows 90 of teeth, and in order to remove the same it is only necessary to spring the latch plate 15 outwardly so that the plate 12 may be swung upon the end of the body plate 5 to its open position shown in Fig. 2 of the 95 drawings. In this movement of the plate 12, the dirt and other foreign matter is removed from the rows of comb teeth. By providing such a cleaning device, it is unnecessary to strike the comb upon an object 100 in order to jar the same and dislodge the foreign matter from the comb teeth, which practice soon results in serious injury to the teeth of the comb which will preclude the further effective use of the device.

105 From the foregoing it will be appreciated that I have produced a very simple, convenient and serviceable cleaning device for curry combs which may be produced at small manufacturing cost, and enables the 110 teeth of the comb to be very easily and quickly cleaned. Owing to the very simple

construction of my invention, it will be obvious that the same is strong and durable in practical use and may be produced at small manufacturing cost.

5 While I have shown and described the preferred construction and arrangement of the several elements employed, it will be understood that the invention is susceptible of considerable modification therein and I
10 therefore reserve the privilege of resorting to all such legitimate changes as may be fairly embodied within the spirit and scope of the invention as claimed.

Having thus described the invention, what
15 is claimed is:

The combination with a curry comb having a plurality of rows of comb teeth and provided with a handle member having par-

allel portions secured upon the body of the comb, of a cleaning plate, links hingedly connecting said plate at one of its ends to one of the parallel portions of said handle member, said plate being provided with a plurality of parallel longitudinal slots to receive the respective rows of comb teeth, and a spring latch member on the other end of said cleaning plate engageable with the body of the comb to retain the cleaning plate in its closed position upon said teeth.

In testimony whereof I hereunto affix my
signature in the presence of two witnesses.

HIRAM R. SUITS.
